UNITED STATES PATENT OFFICE.

GEORGE A. TRUE, OF DETROIT, MICHIGAN.

OVERHEAD TRAVELING CRANE.

SPECIFICATION forming part of Letters Patent No. 517,078, dated March 27, 1894.

Application filed November 14, 1893. Serial No. 490,912. (No model.)

To all whom it may concern:

Be it known that I, GEORGE A. TRUE, a citizen of the United States, residing at Detroit, in the county of Wayne and State of Michigan, have invented certain new and useful Improvements in Overhead Traveling Cranes, of which the following is a specification, reference being had therein to the accompanying drawings.

10 The invention consists in the peculiar construction of the bridge, and the construction and arrangement of the trolley and its actuating devices, and further in the peculiar construction, arrangement and combination of 15 the various parts, all as more fully hereinafter described.

In the drawings, Figure 1 is a side elevation of a bridge and trolley embodying my invention. Fig. 2 is a plan view thereof. Fig. 20 3 is a section through the bridge, showing the trolley in elevation. Figs. 4 and 5 are similar sections of modified forms.

A is the track, B the carriage or bridge, and C its wheels running on the track. Upon 25 this bridge runs a trolley D having a suitable hoist.

E is the actuating shaft for the trolley and E' the actuating shaft for the hoist.

The bridge consists of a main bridge which 30 supports the load, and an auxiliary bridge or rail for supporting the outer end of the actuating shaft or shafts which are provided with suitable wheels F running and supported on the auxiliary rail, having the usual chain 35 wheel and chains for actuating them.

In Figs. 1, 2 and 3 I have shown the bridge formed of end beams *a*, main bridge beams *b c* and an auxiliary rail or bridge *c'*.

In Fig. 4 I have shown the main or load 40 carrying bridge formed of a single I beam *d*, and an auxiliary bridge formed of an I beam *e*.

In Fig. 5 I have shown another modification in which the trolley runs upon the top of an I beam bridge *f* and the auxiliary 45 bridge or rail is formed by the squaring shaft *g*, connecting the drive mechanism at opposite ends of the bridge. This last mentioned

construction is especially adapted for cranes of small span.

By arranging the drive wheels for the trolley and hoist to one side, I am enabled to handle bulky or heated articles without danger and with greater convenience. This construction is also desirable for applying electric or other motors to these drive shafts, as 55 they may be applied between the main bridge and the rail. I have indicated in dotted lines an electric motor thus applied at *J* in Fig. 3.

It is evident from the modifications shown, that the apparatus may be variously constructed, and yet come within the spirit of my invention, which as I understand it, broadly consists in arranging an auxiliary rail beside the bridge, to support the outer end of the actuating shafts of the trolley or hoist. 65

What I claim is—

1. In a crane, the combination of a bridge for supporting the load and the hoist, a rail or auxiliary bridge beside the same and the actuating shaft for the hoist extending over 70 the rail having its outer end supported thereon, substantially as described.

2. In a crane, the combination of a bridge, the trolley thereon and its hoist, of an auxiliary rail beside the bridge, an actuating 75 shaft extending from the trolley over said rail and a wheel running on the rail and supporting the outer end of said shaft, substantially as described.

3. In a crane, the combination of a bridge, 80 the trolley thereon, a hoist supported on the trolley, actuating shafts for the trolley and hoist, an auxiliary rail or bridge separated from and arranged beside the load supporting bridge, wheeled bearings on said rail supporting the outer ends of the shafts, and actuating wheels on the shafts, substantially as 85 described.

In testimony whereof I affix my signature in presence of two witnesses.

GEORGE A. TRUE.

Witnesses:

JAMES WHITTEMORE,
O. F. BARTHEL.
